UNITED STATES PATENT OFFICE.

JOSEPH G. HUYE, OF NEW ORLEANS, LOUISIANA.

BOX.

1,249,099.

Specification of Letters Patent.

Patented Dec. 4, 1917.

Application filed June 30, 1917. Serial No. 177,897.

To whom it may concern:

Be it known that I, JOSEPH G. HUYE, a citizen of the United States, residing at New Orleans, in the parish of Orleans and 5 State of Louisiana, have invented certain new and useful Improvements in Boxes, of which the following is a specification.

This invention relates to collapsible set-up boxes, more particularly to paste-board 10 hat-boxes, candy-boxes and similar receptacles and may be made in any desired form, it being understood of course that the outline of the top and bottom or end portions shall correspond to the cross-sectional form 15 of the body.

The primary object of this invention is to improve the locking means for sectional collapsible set-up boxes consisting of two or more sections, two of which may be easily 20 and securely locked together in accordance herewith. Other objects are to simplify such boxes, reduce their cost of manufacture and increase their durability.

In the accompanying drawings:

25 Fig. 1 represents a perspective view of a box, of octagonal form, in which my invention is embodied, the upper and lower portions being partially broken away;

Fig. 2, a top plan view of the same, with 30 the cover removed;

Fig. 3, a superposed perspective view of portions of the body and the flange or lip 5 carrying the engaging elements;

Fig. 4, a fragmentary sectional view on 35 the line 4—4 of Fig. 2, the wall of the body being broken away to show the inner face of the lip 5 in elevation;

Fig. 5, a sectional view at right angles thereto;

40 Fig. 6, a plan view of a modified form of cylindrical shape with the cover removed, employing a single disk-shape stop glued to the upper inner face of the end section and having its edge at an equal distance, at all 45 points, from the inner face of the lip 5, and having the lugs 7 glued thereto.

Fig. 7 a fragmentary sectional view on the line 7—7 of Fig. 6; and

Fig. 8, an enlarged horizontal sectional 50 view through one of the lugs 11, of the modified form shown in Fig. 6, and the adjacent parts of the body and lip 5.

Referring now in detail to the drawings, the box illustrated consists of three parts 55 or sections, the top A having the usual flange or lip, the body sections 8 snugly fit-

ting into this flange or lip with its upper portion and with its lower portion similarly fitting into the correspondingly shaped flange or lip 5 of the bottom 4.

Each face or wall of the lip or flange 5, in the angular shapes, such as shown, is, preferably, provided with at least two angular openings 6 to receive the correspondingly shaped lugs 7 formed by stamping out on three sides the material of body 8 and bending each pair of such stamped out parts, on their fourth and connected side, back against the adjacent face of body 8, one outside of the other, and securing them in such position by any suitable method or means, such as the staples 9. The position of the lugs 7 on the body 8 corresponds to the position of the holes 6 in the lip or flange 5, so that when the body 8 is slightly deformed and has its lower end portion inserted into the lip 5 of end 4 its lugs 7 will enter the corresponding holes 6 in the lip 5 and the edges of the lugs 7 and the walls of the respective holes 6 will engage and prevent any movement of the parts 4, 5 and 8 with relation to each other, except laterally inwardly or outwardly, so long as the body 8 retains its normal shape.

When the parts 8 and 4 have been assembled as above with the lugs 7 projecting into or through the respective opening 6, the locking flanges 3, formed integral with body 8 and folded inwardly at right angles thereto on scored lines are snapped down to engage with their edges the outer faces of the corresponding stops 1.

These stops 1 are formed by stamping out from the bottom 4 adjacent the lip 5 at an equal distance from the outer face of each stop 2 to the adjacent portion of the inner face of the lip 5 to force the lower portion of the body 8 firmly outwardly thereagainst to hold the lugs 7 in the holes 6 and prevent their escape therefrom.

The width of the flange 3 will be slightly greater than the distance from the outer face of each stop 2 to the adjacent portion of the inner face of the lip 5 to force the lower portion of the body 8 firmly outwardly thereagainst to hold the lugs 7 in the holes 6 and prevent their escape therefrom.

In the modified form a single stop 10,

disk-shape for the cylindrical shape box shown, having its outer edge at an equal distance from the lip 5 at all points, is substituted for the stops 1, being glued to the 6 upper inner face of the bottom 4, or may be secured immovably thereto in any suitable manner.

Also, in this form separate lugs 11 glued to the outer face of body 8, or otherwise 10 immovably secured thereto, are substituted for the lugs 7 above described.

In this form the body 8 and the bottom 4 are imperforate, though of course the lip 5 will need to be provided with the perforations 6 to receive said lugs, the same as in 15 the preferred form.

The disk stop 10 and the lugs 11 will be made preferably of loose rolled paper board about twice as thick as the material used for 20 the body 8. Of course the disk 10 will also serve to reinforce the bottom 4, making it thicker and stiffer.

Any suitable fibrous or metallic material 25 may be used throughout or wherever desired.

Having described my invention, what I claim as new and desire to claim by Letters Patent is:

1. A box comprising a body section and 30 an end section, said sections being provided with interengaging means, the end section receiving the end portion of the body section and having a lip, in combination with a stiff inwardly presented part carried by 35 said body section and a stop held immovably to the inner face of said end section, the distance from between the outer and inner faces of said part being greater than the distance between the outer face of said 40 stop and the inner face of said lip.

2. A box comprising a body section and 45 an end section, said sections having interengaging means, and the end section having a lip, in combination with a stop carried by said end section and immovable with relation thereto, and means carried by said body section and adapted to engage said

stop to force the adjacent portion of the body section outward against said lip.

3. A box comprising a body section and 50 an end section, said sections having interengaging means, and the end section having a lip, in combination with a stop carried by said end section and immovable with relation thereto, and means integral with said 55 body section and adapted to engage said stop to force the adjacent portion of the body section outward against said lip.

4. A box comprising a body section and 60 an end section, said sections having interengaging means and the end section having a lip, in combination with an integral stop carried by said end section and immovable with relation thereto, and means carried by 65 said body section and adapted to engage said stop to force the adjacent portion of the body section outward against said lip.

5. A box comprising a body section and 70 an end section, said sections having interengaging means and the end section having a lip, in combination with an integral stop carried by said end section and immovable with relation thereto, and means integral 75 with said body section and adapted to engage said stop to force the adjacent portion of the body section outward against said lip.

6. A box comprising a body section provided with integral lugs and an end section provided with a lip having holes to receive said lugs and which snugly receives the end 80 portion of said body section, in combination with a stop integral with said end section and held immovably thereto and means integral with said body section adapted to engage said stops to force said body section 85 outward against said lip to hold said lugs in said holes.

7. A box end section fixed in form and having integral stops immovably secured thereto and provided with a lip. 90

In testimony whereof, I have signed my name to this specification.

JOSEPH G. HUYE.
